United States Patent Office

Des. 177,465
Patented Apr. 17, 1956

177,465

BOAT BAILER OR SIMILAR ARTICLE

Walter G. Feik, Houston, Tex.

Application January 13, 1954, Serial No. 28,498

Term of patent 14 years

(Cl. D71—1)

Fig. 1 is a perspective view of a boat bailer embodying my design;

Fig. 2 is a top plan view of the boat bailer of Fig. 1;
Fig. 3 is an elevational view thereof; and
Fig. 4 is a bottom view of the boat bailer.

I claim:

The ornamental design for a boat bailer or similar article, substantially as shown.
